DOORKNOB-ALARM.

1,327,021.

Specification of Letters Patent.

Patented Jan. 6, 1920.

Application filed October 11, 1918. Serial No. 257,750.

To all whom it may concern:

Be it known that I, JAMES M. BUTCHER, a citizen of the United States, residing at Chicago, in the county of Cook and State 5 of Illinois, have invented certain new and useful Improvements in Doorknob-Alarms, of which the following is a specification.

One object of the present invention is to provide a simple, cheap, and easily assembled 10 spring actuated mechanism for developing the vibratory movement in a striker which coöperates with the bell or other sound-producing element in an alarm device; to which end, one feature of the invention consists in providing, upon a suitable base, 15 bearings or mountings for the several elements of the alarm device, such as the spring arbor which carries the master wheel, the multiplying arbor with its driven pinion and transmitting wheel, the third arbor with its driven pinion and ratchet, and the oscillating pallet or escape- 20 ment controlled by the ratchet and which carries the striker; and having these several 25 members of the organization axially introduced into their bearings, or upon their mountings on the base, and overlapped one upon the other (for instance, in the reverse order in which they are above enumerated), 30 so that when they are all brought successively in place they will be held in assembled relation one by another up to the last member to be introduced (for instance, the main arbor) and this will be secured by a 35 readily releasable clip or key.

Another object of the present invention is to provide a novel construction of pendulous mounting, through which to suspend an alarm from a door knob, and by which 40 to release the alarm by pendulous action or change of angular position resulting from partial turning of the door knob; the said mounting to be of a construction that may be produced very cheaply and assembled 45 with minimum labor, mainly by interlocking of the parts, and with minimum use of screws, or the like. To this end, a second feature of the invention consists in providing the knob clamp or hanger with a pendulous rod and a releasing plunger assembled by means of projections and openings in the respective parts, which are engaged by introducing one part through the other while in position angularly displaced

from the normal relative positions of the 55 parts, and made to interlock by swinging the parts to their said normal positions, the pendulous hanger and the releasing plunger being moved in different directions from their assembling to their 60 interlocking positions and being both thereafter connected with the alarm in a manner to prevent return to releasing position.

Still another object of the present invention is to provide a detent for the damper or stop of the alarm device, of such a character that may be moved to a position where it will automatically arrest the stop in its releasing position, once the latter is displaced by the action of the plunger 70 resulting from the pendulous movement, and thereby insure continuance of the alarm even though the alarm may be restored to normal position by the release of the door knob. To this end, a third feature of the 75 invention consists in providing, upon the sleeve of the spring arbor, a friction strap with a detent and a controlling arm projecting therefrom in position to present the detent in the path of the alarm stop, with 80 the arm in position for manipulation in swinging the detent to and from its effective position, the strap embracing the sleeve with sufficient resiliency to hold the detent in either position to which it may be moved. 85

The invention will be more fully understood upon reference to the accompanying drawings, in which one embodiment of each of the several features is disclosed by their illustration.

Figures 1 and 2 are front views of the complete alarm device (a portion of the bell being broken away) shown as applied to the shank of a door knob, Fig. 2 showing the alarm angularly displaced by pendulous 95 action resulting from the turning of the knob.

Fig. 3 is a side elevation of the parts shown in Figs. 1 and 2.

Fig. 4 is a section on the line 4*-4* of 100 Figs. 1 and 3.

Figs. 5 and 6 are, respectively, a face view and a vertical section of the portion of the clamp with which the pendulum rod and releasing plunger are assembled; Fig. 105 5 showing the pendulum rod, and Fig. 6 the releasing plunger, in the positions angularly displaced from their normal positions.

which they respectively assume in being introduced into the recesses formed in the clamp to receive them.

Fig. 7 is a rear view of the alarm device detailing the attachment thereto of the pendulum rod.

Fig. 8 is a front view of the alarm device with the bell removed, and detailing the relation of the detent to the stop which controls the alarm.

Fig. 9 is a side view of the parts shown in Fig. 8.

Fig. 10 is a view detailing the assembly of the detent with the sleeve of the spring arbor; and

Figs. 11 and 12 are, respectively, a rear face view and an axial section detailing the assembly and securing of the spring arbor upon the base.

20 A represents the alarm; B the knob clamp; C the pendulum rod which suspends the alarm from the clamp; D the releasing plunger which converts pendulous motion into an alarm-releasing motion; and E the detent which prevents return of the alarm stop when the clamp resumes its normal angular position with relation to the alarm.

The alarm comprises the bell A¹, and, as more clearly shown in Figs. 8 and 9, the vibrator A², the ratchet A³, the multiplying wheel A⁴, and the main spring arbor A⁵. These several parts intermesh *en train*. Each is mounted upon the usual center bearing, and the parts are made to overlap in such a manner that when assembled, and so long as the main arbor A⁵ is secured against axial displacement, the parts will maintain their assembly and operative relationship; that is to say, the vibrator A² has a portion 40 that is overlapped by the ratchet wheel A³, while the pinion A⁶ of said ratchet wheel, which meshes with the multiplying wheel A⁴, is overlapped by the main wheel A⁷ on the arbor A⁵, as also is the multiplying wheel A⁴. To secure the main arbor A⁵ in its bearing sleeve A⁸ (Fig. 12), the bifurcated clip A⁹, upon the rear face of the base A¹⁰, enters the annular groove A¹¹ of the arbor and is readily releasable therefrom at will. 50 By this mode of assembly screws, rivets, and other time-consuming means are wholly eliminated.

In assembling the alarm with its clamp B, a pendulum rod C, having a T-head C¹, is introduced into the swinging bearing C², to which it is admitted by the radial slot C³ when the pendulum rod is in a position parallel to the plane of the clamp, but angularly displaced from its normal position, and this pendulum rod C is secured to the alarm A by means of the screws C⁴, one of which passes through the slot C⁵ while the other is adapted to receive the fork C⁶, so that but one of the screws need be removed 60 in disassembling the parts.

The releasing plunger D is assembled with the clamp B by introducing its forked ends D¹ through the arcuate slots B³. Each of these slots is in the form of an arc concentric with the upper end of the other slot, so that when the hanger assumes an angular position (for instance, that shown in Fig. 2), the upper end of the slot engages a projection to depress the plunger and release the alarm, while the other projection swings in its arcuate slot to avoid interfering with the depression. The plunger D enters the tubular stem A¹¹ of the alarm and so encounters the stop A¹², which controls the vibrator A² of the alarm, that when the plunger D is depressed, as described, the vibrator A² is released and the alarm will sound.

The plunger D is assembled with the clamp B by introducing the projections D¹ through the slots B³ while (Fig. 6) the plunger is angularly displaced in a direction perpendicular to the plane of the clamp B, the projections D¹ being so offset from the plane of the plunger that when the plunger is swung back toward the plane of the clamp the projections will be (Fig. 4) interlocked with the clamp. Since the lower end of the plunger enters the hollow stem A¹¹, and the pendulum rod C which is also interlocked with the clamp has been secured to the shell of the alarm, it is obvious that the pendulum rod and plunger will remain assembled as described, since neither can execute the relative movement necessary to release it. Obviously, the plunger will be first assembled with the clamp and then introduced with its lower end in the hollow stem A¹¹, after which the pendulum rod will be assembled with the clamp and secured to the back of the shell of the alarm; or, if preferred, since the slot C⁵ and the fork C⁶ are elongated as shown, the pendulum rod C may be first assembled with the screw C⁴ occupying the lower end of the slot C⁵, the plunger D then put in place, the alarm moved upwardly upon the rod C to cause the hollow stem A¹¹ to receive the lower end of the plunger and bring the fork C⁶ into engagement with the lower screw C⁴, after which the screws may be tightened up to hold the parts in the described relation. It will be obvious that the elongated form of slot C⁵ and fork C⁶ provide for exact adjustment of the alarm upon the pendulum rod, and therefore the correct range of displacing movement developed in 110 the stop A¹² by the inserted end of the plunger.

As will best be seen from Fig. 10, the detent E comprises a strap E¹ by which the detent embraces the sleeve A⁸ of the alarm, and which surrounds said sleeve with sufficient resiliency to hold the detent in any adjustment to which it may be moved; also the stop arm E² and the finger lever E³, of which the former is movable into position to arrest 120

the stop A¹² which controls the vibrator A², while the latter presents itself in such position as to conveniently serve for adjusting the detent. The resiliency of the arm E² is such that when the detent is thrown to effective position and the arm E² is arrested by the stop A¹², said arm will be put under tension that will cause it to snap over the stop A¹² as soon as the latter is depressed by 5 the pendulous releasing action of the alarm, and, when so engaged, will prevent return of the alarm stop A¹² even though the alarm is restored to normal position with relation to its clamp, and the alarm will continue to 10 ring until the detent is voluntarily released. Obviously, if the detent is adjusted to its inactive position, release of the alarm by depression of the stop A¹² will be momentary, or continued only so long as the door knob 15 is held in the turned position.

I claim:

1. In an alarm device, the combination of a single base member, and a series of alarm elements each having a bearing 25 through which it is supported wholly by said single base member; each element being assembled with its bearing on the base member by axial movement relative thereto; said elements being assembled in succession and 30 overlapping one another to secure them in place; and the element last assembled with its bearing having means engaging it with and securing it against axial separation therefrom.
2. In an alarm device, the combination of a single mounting member, alarm elements comprising a vibrator, a ratchet wheel controlling said vibrator, and a driving wheel controlling said ratchet wheel; said 35 vibrator, ratchet wheel and driving wheel having each an independent bearing through which it is rotatably supported wholly from said single mounting member, and each being assembled into its said bearing by axial 40 movement relative thereto; said elements being assembled in overlapped relation in the order named, whereby one is secured against axial displacement by another; and means being provided for engaging the driving 45 wheel with and securing it against axial separation from its bearing on the mounting member.
3. In an alarm device, a mounting, a series of alarm elements having bearings upon 50 said mounting and assembled therewith by relative axial movement between each member and its bearing; said alarm elements being engaged *en train*, assembled successively, and overlapped one upon another in 55 series, and means for securing the last alarm element upon the mounting consisting of an arbor carrying said alarm element and a spring clip engaging said arbor.
4. In a knob alarm, the combination of a 60 support, an alarm device, and a connection

between the support and the alarm device united with said support through the medium of a projection on one part entering an opening on the other part, assembled therewith while in a position angularly displaced from the normal positions of the parts, and interlocked by movement from the assembling to the normal position. 70

5. In an alarm device, the combination of an alarm, a support, and connecting members between the alarm and the support secured to the support through the medium of openings and projections assembled by introducing the projections into the openings while the connecting members are angularly 75 displaced from their normal positions and interlocked by their movement from such assembling positions to their normal positions, the assembly positions of the respective connecting members being displaced in 80 different directions from their normal positions.

6. In an alarm device, the combination of an alarm, a support, and connecting members between the alarm and the support 90 secured to the support through the medium of openings and projections assembled by introducing the projections into the openings while the connecting members are angularly 95 displaced from their normal positions and interlocked by their movement from such assembling positions to their normal positions, the assembly positions of the respective connecting members being displaced in different directions from their 100 normal positions; said connecting members having each an engagement with the alarm that prevents its return from normal position.

7. In an alarm device, the combination of an alarm, a support, and connecting members between the alarm and the support secured to the support through the medium of openings and projections assembled by introducing the projections into the openings while the connecting members are angularly 105 displaced from their normal positions and interlocked by their movement from such assembling positions to their normal positions, the assembly positions of the 110 respective connecting members being displaced in different directions from their normal positions; said connecting members having each an engagement with the alarm that prevents its return from normal position, the engagement of one of said connecting members with the alarm being through a sliding movement longitudinally of the member and the other being through the medium of a releasable connection. 115

8. In an alarm device, the combination of a support, an alarm, a pendulum rod connecting the alarm with the support, and a releasing plunger introduced between the support and the alarm; said releasing plunger 120 125 130

having a longitudinal sliding movement in the alarm for releasing the same and having a pair of projections intersecting the plane of and adapted to bear against the support at points radially removed from the center of oscillation of the pendulum rod.

9. In an alarm device, the combination of a support, an alarm, a pendulum rod connecting the alarm with the support, and a releasing plunger introduced between the support and the alarm; said releasing plunger having a longitudinal sliding movement in the alarm for releasing the same and having a pair of projections intersecting the plane of and adapted to bear against the support at points radially removed from the center of oscillation of the pendulum rod; said support having slots to receive said projections, and said projections being deflected to permit them to pass through the slots and lie on the opposite side of the support from the plunger.

10. In an alarm device, a support, an alarm, a pendulum rod connected with the alarm and having a swinging bearing upon the support, and a releasing plunger having a longitudinal releasing movement in the alarm; said plunger having a bifurcated end by which it penetrates the supports, the projections of said end being deflected to permit them to lie on the opposite side of the support from the plunger; said plunger being assembled from a position projecting angularly outward from the support and being interlocked therewith by movement into position parallel with the plane of the support.

11. In an alarm device, the combination of a support, an alarm, a releasing plunger having longitudinal sliding movement in the alarm and bearings at two spaced points upon the support, and a pendulum rod secured to the alarm and having an oscillating bearing upon the support at a point intermediate of the two bearings of the plunger thereon; said pendulum rod having a T-head entering its bearing upon the support; said last-named bearing being shaped to admit the T-head when the pendulum rod is in a position angularly displaced from that in which it is secured to the alarm.

12. In an alarm device having a releasing

stop, a detent constructed to engage said stop and having a setting movement which 55 presses it toward position to engage the stop; said detent being resilient whereby it moves into engagement with the stop when the latter is moved to release the alarm.

13. In an alarm, a releasing stop normally resisting action of the alarm, means for displacing said stop to release the alarm to its action, and a detent carrying means for engaging the stop in its alarm-releasing position, movable into and out of effective 65 position at will, and having its stop engaging means resiliently supported whereby it automatically enters into engagement with the stop when set to control the latter.

14. In an alarm, the combination with a 70 bearing sleeve, a resilient strap encircling said bearing sleeve, an arm projecting from said strap, a detent on said arm, a stop for controlling the alarm, and means for adjusting the detent to and from position to 75 engage the stop.

15. In an alarm, the combination with a bearing sleeve, a resilient strap encircling said bearing sleeve, an arm projecting from 80 said strap, a detent on said arm, a stop for controlling the alarm, and means for adjusting the detent to and from position to engage the stop; said stop being in the path of the detent when the stop is in alarm-arresting position, said arm being resilient 85 and throwing the detent in the path of the stop when the stop assumes its alarm-releasing position.

16. In an alarm, the combination with a bearing sleeve, a resilient strap encircling 90 said bearing sleeve, an arm projecting from said strap, a detent on said arm, a stop for controlling the alarm, and means for adjusting the detent to and from position to engage the stop; said stop being in the path 95 of the detent when the stop is in alarm-arresting position, said arm being resilient and throwing the detent in the path of the stop when the stop assumes its alarm-releasing position; said strap also carrying an 100 arm controlling the position of the detent arm.

Signed at Chicago, Illinois, this 28th day of September, 1918.

JAMES M. BUTCHER.
